UNITED STATES PATENT OFFICE.

CONSTANT CASIMIR BALLIN, OF PARIS, FRANCE.

SPRING-HUB FOR VEHICLE-WHEELS.

SPECIFICATION forming part of Letters Patent No. 611,095, dated September 20, 1898.

Application filed November 13, 1897. Serial No. 658,473. (No model.) Patented in France December 21, 1896, No. 262,405; in England December 21, 1896, No. 5,527, and in Belgium January 11, 1897, No. 125,669.

To all whom it may concern:

Be it known that I, CONSTANT CASIMIR BALLIN, of the city of Paris, France, have invented an improved flexible hub applicable 5 to the wheels of vehicles generally and more particularly to existing wheels, (for which I have obtained Letters Patent in France for fifteen years, dated December 21, 1896, No. 262,405; in Belgium, for fifteen years, dated 10 January 11, 1897, No. 125,669, and in England, for fourteen years, dated December 21, 1896, No. 5,527,) of which the following is a full, clear, and exact description.

The invention forming the subject of the 15 present application relates to an elastic or flexible hub of improved construction applicable to the wheels of vehicles of every description, and more particularly to existing wheels. Wheels of the latter class need not 20 be changed or undergo any essential alteration in order to be refitted in accordance with this invention, it being only necessary to enlarge the diameter of the aperture or bore of the hub and to reduce its length to adapt it 25 for the reception of the improved flexible device. The flexible arrangement enables the wheel to be strengthened at its weak or reduced part, its center being tightly compressed between two metal parts, which protect it from injury. Besides, a wheel fitted 30 with the elastic device possesses great strength, while its elasticity is better distributed than over its circumference, all shocks or thrusts being relieved by an india-rubber 35 cushion interposed between the wheel and the axle-journal, which consequently is not liable to be broken. This arrangement also obviates the inconveniences attending the application of india-rubber to the felly of the 40 wheel, the rubber so applied being liable to rapid deterioration and apt to cause the wheels to slip upon wet roadways.

The invention will be clearly understood 45 by reference to the accompanying drawings, which show, by way of example only, an arrangement carried out in accordance with my invention.

In the drawings, Figure 1 is an elevation of 50 an existing carriage-wheel to which the improved flexible-hub arrangement is applied.

Fig. 2 is a horizontal section thereof, taken on the line 1 2 of Fig. 1. Fig. 3 is a vertical section of the flexible hub separately drawn to an enlarged scale. Fig. 4 illustrates the manner of applying the flexible-hub arrangement 55 to the metal wheels of motor-cars. Fig. 5 is a horizontal section taken on the line 3 4 of Fig. 4, and Fig. 6 is a vertical section of the elastic hub separately and drawn to an enlarged scale. 60

In the several figures like parts are indicated by similar letters of reference.

The method of applying the improved flexible arrangement to the wooden hub of an existing wheel—say, to the wheel of a wagon or 65 carriage, as is assumed to be the case in the example given at Figs. 1 to 3—is as follows: The outside parts of the wooden hub are first removed, so as to reduce its length, and the portion *a* thereof only is retained. The diameter of the opening or bore through which the axle-journal passes is then enlarged for the reception of the improved flexible device. After interposing the part *b* of the india-rubber sleeve between the bushing *c* of the hub 70 and the portion *d* of the casing these two halves of the device are inserted into the enlarged bore of the wooden hub *a*, and a cap *e* is then screwed onto the part *d* of the casing. After inserting the part *b'* of the india-rubber 75 sleeve between the portions *c'* and *d'* of the bushing and casing, respectively, these pieces are united by screwing to the corresponding parts *b* and *c*, and upon screwing the cap *e'* onto the part *d'* of the casing the 80 wooden hub *a* will be firmly compressed by the casing and the hoops *f* will be prevented from shifting. By these means a wheel of 85 great flexibility and strength is obtained, while no change need be made in the usual 90 method of lubrication.

In applying the improved arrangement to the metal wheels of motor-carriages, as exemplified at Figs. 4 to 6, the india-rubber sleeve *b* is interposed between the wheel-bushing *c* and the outer case *g*, wherein the spokes *h* are set. The portion *c'* of the bushing is screwed into the corresponding part *c*, after which the cap *i* is screwed into the interior of the case *g*. 95 100

Where the improved flexible hub is employed, the wheel may be fitted with balls *k*, adapted to roll around the journal *l* of the axle.

5 It will be understood that the shapes and dimensions of the parts, the details of construction, and the materials employed in the manufacture of the improved device may vary without departing from the principle of 10 the invention.

I claim—

1. In a vehicle-hub, the combination of a bushing formed by two sections having their inner ends engaging each other and each provided with a flange at its outer end, a casing, 15 an elastic cushion between the casing and bushing, and a screw-threaded cap engaging the casing, substantially as described.

2. In a vehicle-wheel, the combination of a 20 flanged bushing formed of two sections having an interlocking engagement with each other, a casing formed of two sections having an interlocking engagement with each other, a cushion between the casing and bushing, 25 and caps screwing on the casing, substantially as described.

3. In a vehicle-wheel hub, the combination of a two-part flanged bushing screwing one onto the other, a two-part casing screwing 30 one upon the other, a two-part cushion be-

tween the casing and bushing, and caps screwing on the casing, substantially as described.

4. The combination with a wooden hub, 35 of a two-part flanged bushing, a two-part casing, one part of the casing projecting over the hub, a two-part cushion between the casing and bushing, a cap screwing onto the end of one section of the casing, and a second cap screwing onto the other section of the casing and projecting over the end of the hub opposite 40 that over which the section of the casing projects, substantially as herein shown and described.

5. The combination of the wheel having a sleeve forming an inner lining for the hub, a 45 cap screwing on said sleeve, an interior, transversely-divided sleeve whose ends are engaged respectively by the first-named sleeve and its cap, and an elastic cushion located between the two sleeves and between flanges on the 50 interior sleeve, substantially as described.

The foregoing specification of my improved flexible hub applicable to the wheels of vehicles generally, and more particularly to existing wheels, signed by me this 23d day of 55 October, 1897.

CONSTANT CASIMIR BALLIN.
